TIRE HOLDER FOR HOLDING A PNEUMATIC TIRE ON A WHEEL RIM

Borje Christer Carl-Gustav Victor, Trelleborg, Sweden,
assignor to Trelleborgs Gummifabriks AB, Trelleborg,
Sweden

Filed Sept. 5, 1974, Ser. No. 503,548

Claims priority, application Sweden Mar. 11, 1974

Term of patent 14 years

Int. Cl. D12—15

U.S. Cl. D12—153

FIG. 1

FIG. 2

FIG. 4

FIG. 3

FIG. 1 is a top plan view of a tire holder for holding a pneumatic tire on a wheel rim showing my new design;

FIG. 2 is a side elevational view thereof, the opposite side being a mirror image of the side shown herein;

FIG. 3 is a bottom plan view thereof; and

FIG. 4 is an end elevational view thereof, the opposite side end being a mirror image of the end shown herein.

I claim:

The ornamental design for a tire holder for holding a pneumatic tire on a wheel rim, as shown.
